UNITED STATES PATENT OFFICE.

FRANK L. HARMON, OF BEVERLY, MASSACHUSETTS.

EYELETING-MACHINE.

1,169,399.

Specification of Letters Patent. Patented Jan. 25, 1916.

Application filed April 20, 1914. Serial No. 833,014.

To all whom it may concern:

Be it known that I, FRANK L. HARMON, a citizen of the United States, and resident of Beverly, county of Essex, Commonwealth of Massachusetts, have invented an Improvement in Eyeletting-Machines, of which the following description, in connection with the accompanying drawings, is a specification, like characters on the drawings representing like parts in each of the several views.

This invention relates to eyeletting machines of that type wherein the holes are punched in the stock and the eyelets inserted and clenched individually with an automatic feed of the material for spacing the eyelets between successive eyeletting operations.

The general object of the invention is to provide an improved machine of this type of exceptionally simple construction, capable of rapid accurate operation, wherein all the working parts operate from one side of the material support, such material support including the punch block and clenching surface being preferably solid and imperforate.

More especially the invention has to do with an improved eyeletting machine of the general type stated in which an eyelet set with a spindle therein is normally held directly above a clenching surface for operative movement toward and from the same, and a punch-carrier with a punch held therein is located in operative relation to a punch block, the punch-carrier being so mounted and operated as to impart to the punch a cycle of movement wherein it first operates against the punch block to punch the material, then moves laterally a predetermined amount to a position under the spindle and set to feed the material and position the hole punched in line with the spindle and set, and is then moved out from under the spindle and set and returned to initial position. In connection with the operative movement of the spindle and set toward and from the clenching surface I preferably provide means whereby the eyelet may be taken up from a race way by the spindle as it descends and inserted in the eyelet hole, the set in its further movement clenching the eyelet against the relatively stationary clenching surface.

The above and other objects and features of the invention will be better understood

from the following detailed description taken in connection with the accompanying drawings and will be thereafter pointed out in the appended claims.

Referring to the drawings: Figure 1 is a plan view of a machine constructed in accordance with my invention; Fig. 2 is a side elevation thereof with a small part broken away; and Fig. 3 is an enlarged sectional detail of the immediate working parts.

At the front of a suitable base 10 is mounted a stand 11 constituting a material support and shown as equipped with a hardened plate or block 12 at its top, the face of which constitutes a punch block and also has a portion formed to serve as a clenching surface. The material *a* is slideable over this face, being gaged transversely by an upstanding backing piece 13 and is pressed down on to the support face by a spring presser foot 14.

A hollow punch 15 is mounted to move toward and from the punch block face of the plate 12 and also laterally thereof, and is for this purpose threaded in the outer end of a lever 16 fulcrumed on horizontal journals 17 which are formed in a journal block 18 which in turn is mounted to swing on a vertical axis, having for this purpose an axis bolt 19 journaled in the base. For imparting the requisite movements to the lever 16 and hence to the punch 15, I form the inner end of the lever of rounded ball shape as seen at 20 adapted to be acted on by a peripheral cam 21 fixed on a prime drive shaft 22 horizontally journaled in the base. Suitable means, herein shown as a spring 23 fixed to the post 18 and pressing upward on the outer portion of the lever, may be employed for returning the punch upward and holding the inner lever end against said cam. The rounded lever end 20 is also acted on by a lateral cam face 24 being drawn toward such face by a coil spring 25 pulling on the outer end of the lever and anchored to an adjusting screw 26 carried in a post 27 upstanding from the base. The extent to which the lever 16 may swing under the action of the spring 25 and as permitted by the cam 24 is limited by a stop pin 28 adjustable in a post 29 upstanding from the base, the adjustment of this stop serving to determine the initial or punching position of the punch as later described. A second lever 30 is journaled at 31 for movement on a horizontal axis. This

lever had adjustably fixed at its outer end a set 32, the set being shown as adjustably threaded in the lever end. This set is hollow and has projecting therefrom a spindle 33 shown as equipped with an enlarged head 34 slidable in the hollow of the set and pressed outward by a coil spring 35 which reacts against a cap nut 36; this nut also serving as a lock nut to hold the set secure in the lever end. The inner end of lever 30 is shown as equipped with a laterally extending roller 37 which operates in a cam path 38 of a cam member 39 fixed on the shaft 22.

The spring presser foot 14 extends laterally beneath the path of the punch in its lateral movement as at 40 and this lateral extension is forked or slotted as seen at 41 to permit the operation of the punch therethrough. The material support plate 12 which preferably has its surface plane and smooth is formed underneath the set with a clenching surface indicated at 42 consisting of a concave annular groove of a size and contour adapted to engage the ends of 25 the eyelets and spread them outward to clench against the inner side of the material.

It may now be understood that as the shaft 22 is rotated in the direction of the arrow seen in Fig. 2, the punch 15 will be 30 moved downward to punch the hole in the material by the raised portion 21^b of cam 21 which follows a concentric portion 21^a. For this operation the punch may be nicely adjusted so as to just come against the punch 35 block surface by its threaded engagement with the end of lever 16 and it may be secured in such adjusted position by a transverse clamp screw 43 which may press against the punch with an interposed wear 40 pad of rawhide or the like. After the punching operation the punch is slightly relieved from the punch block by a very slightly reduced portion 21^c of the cam which portion continues concentric for a substantial arc 45 to hold the punch engaged in the material though relieved from the punch block surface, while it feeds the material laterally. For this operation a raised portion 24^b succeeding a plane lower portion 24^c of lateral 50 cam 24 comes into play, moving the punch laterally to feed the punched hole into line with the spindle and set. It will be observed that the outer end 16^a of lever 16 is cut away at its top so as to afford clearance permitting 55 it to swing the punch to proper position underneath the set. The punched hole being thus positioned in line with the spindle and set the punch is raised by the action of spring 23 on the punch lever 16, a descent 60 21^d on cam 21 permitting this withdrawal, this cam portion merging into the concentric reduced portion 21^a which leaves the punch withdrawn while it is returned laterally to initial position. This lateral returning of 65 the punch is effected by spring 25, a descend-

ing portion 24^e of cam 24 permitting this movement. The extent to which the punch may swing back laterally, *i. e.*, its punching position, it is determined by the adjustable stop 28 which may thus vary the punching position; it being understood that as the punch block is an extended plane surface, different portions thereof may serve as a backing for the action of the punch. The purpose of thus varying the punching position is to feed the material predetermined amounts variable as required to space the eyelets the desired distance apart. This means of varying the eyelet spacing by varying the punching position of the punch 80 is desirable in the present construction since the other limit of lateral punch movement is a fixed one as required to position the punched hole in line with the spindle and set. 85

In the broader aspects of the invention, the eyelets *b* may be supplied in any desired way, but I preferably provide an eyelet race way indicated at 44 adapted to feed a line of eyelets to position so that the foremost one will be picked off and threaded on the spindle as it descends to position it in the punched hole. I am aware that details of construction may be varied considerably without departing from the spirit 95 or essential attributes of the invention and I therefore desire the present embodiment to be considered as illustrative and not restrictive referring rather to the appended claims to indicate the scope of the invention. 100

Having described my invention, what I claim as new and desire to secure by Letters Patent is:

1. An eyeleting machine, comprising a material support having a substantially continuous, smooth, and plane surface, a portion of which constitutes a punch block and with a stationary clenching surface formed thereon, a set equipped with a spindle, movably mounted in co-operative relation with 105 said clenching surface, a punch movably mounted to punch holes in the material against said punch block and also for lateral movement to bring it with the punched hole at one limit thereof in line with said 110 set and at the other limit thereof laterally away therefrom the distance the eyelets are to be spaced, and mechanism for imparting said movements of the punch and set. 115

2. An eyeleting machine, comprising a material support having a substantially continuous, smooth, and plane surface, a portion of which constitutes a punch block and with a stationary clenching surface formed thereon, a punch mounted for movement against and 120 away from said punch block and also for lateral movement while engaged in the material, the extent of such lateral movement being such as to position the punched hole over the clenching surface at the limit there- 125 130

- of, means for imparting said movements, a set with a spindle projecting therefrom mounted to clench the eyelets in the punched holes against said clenching surface, and operating means for said set, the mounting and operating means of said punch being such as to move it alternately under said set and laterally away therefrom.
3. An eyeleting machine, comprising a material support having a substantially continuous, smooth, and plane surface, a portion of which constitutes a punch block and with a stationary clenching surface formed thereon, a punch mounted and equipped with operating means for punching holes in the material against said punch block and also for lateral movement while engaged in the material to position the punched hole over said clenching surface, and a set with a spindle projecting therefrom separately mounted and equipped with operating means for moving it toward and from said clenching surface to clench the eyelets in the punched holes against said clenching surface.
- 25 4. An eyeleting machine, comprising a material support having a substantially continuous, smooth, and plane surface, a portion of which constitutes a punch block and with a stationary clenching surface formed thereon, a set movably mounted to coöperate with said clenching surface, a punch movably mounted to operate against said punch block for punching holes in the material and also for lateral movement to feed the material, said lateral punch movement being such as to bring it and the punched hole at one limit in line with the set and at its other limit a lateral distance therefrom corresponding to the spacing of the eyelets, mechanism for imparting said movements of the punch and set, and means for varying one of the limits of punching movement to vary the eyelet spacing.
5. An eyeleting machine, comprising a material support equipped with a punch block and a clenching surface, a punch and a set having lever mountings side by side for coöperation with said punch block and clenching surface respectively, the lever carrying said punch being swiveled to move the punch laterally, means for operating the set,
- mechanism for operating the punch to punch the holes and also to move the punch laterally to bring it at one limit of movement while engaged in the work in line with the set, separate yielding means for returning the punch to its other limit of movement, and an adjustable stop for varying the last named limit of movement to determine the punching position and vary the spacing of the eyelets.
6. An eyeleting machine, comprising a material support formed as an imperforate plate or block with a portion thereof constituting a punch block and with a stationary clenching surface formed thereon, a punch and a set movably mounted side by side on the same side of said material support for coöperation with said punch block and clenching surface respectively, means for imparting operative movements to the punch and set, and means for moving the punch laterally to position it at one limit of movement in line with the set and at its other limit of movement a distance therefrom corresponding to the spacing of the eyelets.
7. An eyeleting machine, comprising a material support formed as an imperforate plate or block with a portion thereof constituting a punch block and with a stationary clenching surface formed thereon, a punch and a set movably mounted side by side on the same side of said material support for coöperation with said punch block and clenching surface respectively, means for imparting operative movements to the punch and set, means for moving the punch laterally to position it at one limit of movement in line with the set and at its other limit of movement a distance therefrom corresponding to the spacing of the eyelets, the latter limit of movement being the punching position, and means for varying said punching position.

In testimony whereof, I have signed my name to this specification, in the presence of two subscribing witnesses.
